ILLUMINATED MAGNIFYING GLASS

Alexander Zalman, 80—39 192nd St.,
Jamaica, N.Y. 11423

Filed June 9, 1969, Ser. No. 17,594

Term of patent 14 years

Int. Cl. D16—08, 99

U.S. Cl. 57—1

FIG. 1

FIG. 3

FIG. 2

FIG. 4

FIG. 5

FIG. 6

FIG. 1 is a front perspective elevational view of an illuminated magnifying glass, showing my new design; FIG. 2 is a rear perspective elevational view thereof;

FIG. 3 is a side elevational view thereof;

FIG. 4 is a bottom plan view thereof;

FIG. 5 is a front perspective view of a modified embodiment of the invention;

FIG. 6 is a rear elevation of the modified embodiment.

The side elevational top and bottom plan views of both embodiments are identical.

I claim:

The ornamental design for an illuminated magnifying glass, substantially as shown and described.
